UNITED STATES PATENT OFFICE.

FREDERICK F. FIELD, OF PROVIDENCE, RHODE ISLAND.

FAUCET-VALVE.

SPECIFICATION forming part of Letters Patent No. 757,731, dated April 19, 1904.

Application filed April 5, 1901. Serial No. 54,523. (No model.)

To all whom it may concern:

Be it known that I, FREDERICK F. FIELD, a citizen of the United States, residing at Providence, in the county of Providence and State 5 of Rhode Island, have invented a new and useful Improvement in Faucet-Valves, of which the following is a specification.

This invention has reference to an improvement in valves controlling the discharge of liquid under pressure, and it is particularly applicable to faucets for drawing water under high pressure.

The object of the invention is to secure the slow closing of the valve to prevent injury to the valve and valve-seat.

The invention consists in the peculiar and novel construction comprising a dash-pot whereby the closing of the valve is controlled, as will be more fully set forth hereinafter.

Figure 1 is a vertical sectional view of a faucet containing my invention. Fig. 2 is a sectional view of a modified form of the dash-pot and valve-stem. Fig. 3 is a side view of the cupped sleeve supporting the valve-stem.

In the drawings the valve and valve-stem are shown in the vertical position as used on washstands; but they may be and are frequently placed in the horizontal position. In illustrating my invention I have shown a valve sliding in a perforated sleeve to protect the valve against the blow of the water-hammer; but I do not wish to confine myself to this construction.

In the drawings, a indicates the inlet portion of the faucet connecting with the water-supply; a' , the valve-seat; a'' , a case usually made of spheroidal shape; a^3 , the discharge-duct, and a^4 the valve-stem branch.

In the preferred construction, as shown in Fig. 1, the inlet portion a is formed of a cylinder or tube having a screw-thread for connecting the same with the supply-pipe at one end and on the other a screw-thread for connecting the inlet portion with a screw-threaded boss on the elbow portion. By this construction the parts connected with the valve may be inserted and adjusted to the case or spheroidal portion a'' , and then the connection with the inlet-chamber may be made.

The valve b in the simplest form may be

connected with the valve-stem b' , which is provided with a shoulder having an annular recess forming the cup b^2 , from the center of which extends the stem b^3 , having on its outer end the operating-button b^4 . The stem b^3 extends through and may slide longitudinally in the sleeve b^5 , secured in the branch a^4 and having the inverted cup b^6 . The inverted cup b^6 fits into the cup b^2 with a loose sliding fit in the preferred form shown in Fig. 1 and in the modified form shown in Fig. 2. The inverted cup b^6 fits over the collar b^7 on the valve-stem with a loose sliding fit. By "loose sliding fit" I mean such a fit as will permit water to enter the cup when the valve is open and water is flowing through the faucet and will sufficiently retard the outflow of the water to prevent the valve from seating itself with a blow.

In any form of valve for self-closing faucets it is essential that the valve be seated gradually to prevent the destruction of the valve or valve-seat, and when used under the high pressure used in most cities a yielding resistance to the closing of the valve is essential.

As shown in Fig. 1, water will enter the cup b^2 , also rising in the cup b^6 , but not sufficient to fill the same, thereby leaving an air-space above the water. When now the valve is returned to its seat or closed by the water-pressure, the valve will be cushioned against the water-hammer by reason of the water contained in the cup b^2 acting to compress the air contained in the upper part of the cup b^6 .

I wish to be understood as not claiming herein the subject-matter of the valve b and its cylindrical casing with the spirally-arranged ports, as such matter is claimed in my copending application for United States Patent, filed on even date herewith, Serial No. 54,524.

Having thus described my invention, I claim as new and desire to secure by Letters Patent—

1. The combination of an inlet-pipe; an outlet-pipe and a chamber connecting the two said pipes, a valve located within the inlet-pipe and controlling the communication of the same with said chamber, a reciprocating valve-operating stem mounted through said chamber and adapted to push upon the valve to open

it and to be returned by the valve as it closes under pressure of the fluid in the inlet-pipe, the said valve being provided with telescoping oppositely-arranged recessed members constituting a telescoping cushioning device, substantially as and for the purpose set forth.

2. The combination of an inlet-pipe, an outlet-pipe and a chamber connecting the two said pipes, a valve located within the inlet-pipe and controlling the communication of the same with said chamber, a reciprocating valve-operating stem mounted within said chamber and adapted to push upon the valve to open it and to be returned by the valve as it closes under pressure of the liquid in the inlet-pipe, the said valve-stem comprising a rod and a fixed tubular bearing through which the rod slides, the said bearing projecting into the chamber and being recessed at its inner end to form a liquid-cushioning pocket, a cup-shaped body adapted to receive the liquid in the recess thereof and fixed upon said rod within the chamber and projecting outwardly and inclosing the inner end of said bearing and forming a loose fit therewith and telescoping with said bearing to form a cushioning device, substantially as and for the purpose set forth.

3. The combination of an inlet-pipe, an outlet-pipe and a chamber connecting the two said pipes, a valve located within the inlet-pipe and controlling the communication of the same with said chamber, a reciprocating valve-operating stem b^3 , mounted within said chamber and adapted to push upon the valve to open it and to be returned by the valve as it closes under pressure of the liquid in the inlet-pipe, the said valve-stem comprising a rod, and a fixed tubular bearing b^5 through which the rod slides, the said bearing projecting into the chamber and being recessed at its inner end to form a liquid-cushioning pocket b^6 , a cup-shaped body b^2 fixed upon said rod within the chamber and projecting outwardly and inclosing the inner end of said bearing and forming a loose fit therewith and telescoping with said bearing whereby a telescoping cushioning device is formed, substantially as and for the purpose set forth.

In testimony whereof I have signed my name to this specification in the presence of two subscribing witnesses.

FREDERICK F. FIELD.
